UNITED STATES PATENT OFFICE.

JAMES C. BENNETT, OF DETROIT, MICHIGAN.

BLOWER FOR BOILERS.

1,139,630.

Specification of Letters Patent. Patented May 18, 1915.

Application filed October 28, 1914. Serial No. 868,925.

To all whom it may concern:

Be it known that I, JAMES C. BENNETT, a citizen of the United States of America, residing at Detroit, in the county of Wayne and State of Michigan, have invented certain new and useful Improvements in Blowers for Boilers, of which the following is a specification, reference being had therein to the accompanying drawings.

This invention relates to blowers for boilers and has for its object to provide a blower that can be advantageously used in connection with a boiler of the water tube type. The drawings illustrate a blower especially designed for the well known type of "Wicks" boiler, wherein a plurality of spaced vertically extending tubes are mounted in the path of travel of gases and other products of combustion. As the tubes are located within the path of travel of products of combustion, the outer surfaces of the tubes quickly collect soot particles carried by such product, thereby preventing the maximum application of heat to the tubes.

To prevent the accumulation of soot, scale or incrustations upon the tubes of a vertical boiler, I have devised a reciprocal, rotary and oscillatory apparatus that can be installed without materially altering the construction of a boiler of the vertical type. The apparatus embodies a reciprocal steam injecting member, a rotary injector head, and oscillatory ejectors or nozzles. The reciprocal steam injecting member permits of the steam ejectors or nozzles being projected into the combustion chamber of a boiler for cleaning the chamber and the flues, and retracting the same therefrom so as to clear the chamber in order to prevent the ejectors or nozzles from being burned.

The rotary injector head of the apparatus permits of the steam ejectors or nozzles being whirled or revolved in the combustion chamber of the boiler to insure an equal distribution of steam and a thorough cleansing of the tubes or flues. This is further enhanced by the oscillatory movement of the steam ejectors or nozzles, such movement producing radial fan shaped steam jets that impinge the tubes or flues with such force or pressure as to remove all soot particles that accumulate thereon.

In the general make up of my blower, the parts are constructed with a view of reducing the cost of manufacture and at the same time retain features by which safety, dur-

ability, simplicity and ease of assembling are secured, and with such ends in view, my invention resides in the novel construction, combination and arrangement of parts to be hereinafter specifically described and then claimed; this specification being directed more particularly to the preferred form of construction illustrated by the drawings, wherein—

Figure 1 is a side elevation of the blower attached to a boiler setting and partly broken away and partly in section, showing the reciprocal steam injecting member in a retracted position; Fig. 2 is a plan of a portion of the blower illustrating a locking device for the reciprocal steam injecting member; Fig. 3 is a view of the inner end of the blower; Fig. 4 is a side elevation of a portion of the blower, illustrating a modified form of locking means for the reciprocal steam injecting member; Fig. 5 is a vertical sectional view of a portion of the vertical boiler illustrating diagrammatically the preferable arrangement of my improved blowers relative to the tubes or flues of the boiler; Fig. 6 is a horizontal sectional view taken on the line VI—VI of Fig. 5; Fig. 7 is a front elevation of a door frame adapted to form part of the boiler setting; Fig. 8 is a cross sectional view of the same; Fig. 9 is an enlarged perspective view of a portion of the rotary injector head, illustrating by dotted lines an adjusted position of the oscillatory steam ejectors or nozzles; Fig. 10 is a perspective view of disassembled parts of the injector head; Fig. 11 is a diagrammatic view illustrating various positions of the rotary injector head and the oscillatory steam injectors or nozzles thereof; and Fig. 12 is an elevation of a detached door or shutter.

As an instance of the installation, particularly the location, of my blowers relative to a boiler of the vertical type, there is illustrated in Figs. 5 and 6 a chamber 1 containing vertically extending tubes or flues 2 and the walls 3 of the chamber or the boiler setting are provided with a plurality of openings or doorways 4 into which the blowers can be projected for subjecting the flues or tubes 2 to blasts or jets of steam. As shown, a plurality of the openings or doorways 4 are radially disposed in a horizontal plane whereby a battery of blowers 110 can be located in proximity to the upper ends of the tubes or flues 2, and other open-

ings are diametrically disposed contiguous to the lower end of the tubes or flues. This arrangement is preferable for a boiler of the "Wicks" type, but can be modified for 5 various types of boilers.

In each opening or doorway 4 there is mounted a door frame 5 and bolted or otherwise connected to said frame, as at 6 is a lining 7 for the walls of the opening or 10 doorway 4. This lining is of metal and is made detachable in order that the frame 5 can be used in connection with boiler settings or walls of various thicknesses, it only being necessary to use a lining of sufficient 15 length to approximately extend the length of an opening or doorway. The frame 5 has diametrically opposed socket members 8 or anchoring bolts or tie rods (not shown) employed for securing the frame 5 to the boiler setting or wall 3. The lower edge of the frame 5 has an apertured lug 9 and pivotally connected thereto is a slide door or shutter 10 provided with a handle or knob 11. The door or shutter 10, in a closed position, 20 engages a slotted rest or keeper 12 forming part of the lower edge of the frame 5, and the door or shutter is closed during the operation of the boiler and when the blower is not in use.

The upper edge of the frame 5 has an extension 13 supporting an outwardly extending casing 14, which has a steam connection 15. The outer end of the casing 14, is provided with a tubular telescopic member 16 35 and mounted upon the outer end of said member is a stuffing box 17. The stuffing box 17 has the upper side thereof provided with a boss 18 and a staple 19. Connected to the staple 19 is a hanger 20, preferably 40 in the form of a turn buckle, and said hanger is connected to a staple 21 secured to the boiler setting or wall 3 above the opening or doorway 4 thereof. The turn buckle 20 permits of the outer end of the telescopic member 45 16 being adjusted whereby the casing 14 and said member can be maintained in a horizontal plane at right angles to the boiler setting or wall 3.

The stuffing box 17 is of the conventional 50 form containing packing 22 and a gland 23, and slidable through said stuffing box into the telescopic member 16 is the tube or pipe 24 of a reciprocal steam injecting member, which has been generally designated 25. 55 The outer end of the tube or pipe 24 has a U or return connection 26 provided with a short tube or pipe 27, an elbow 28, and another short tube or pipe 29 supporting a combined stuffing box and housing 30 directly beneath the telescoping elements or the reciprocal member 25.

The housing 30 longitudinally aligns with the opening or doorway 4 and the inner end thereof is provided with an interior annular 65 flange 31 and a peripheral flange 32. Se-

cured to the peripheral flange 32 is a gland 33 retaining packing 34 against the flange 31, and said flange, the packing 34 and the gland 33 surrounds the tubular member 35 of a rotary injector head 36. The outer end 70 of the member 35, within the housing 30, has a collar 37 to abut the flange 31 of the housing and mounted upon the tubular member 35 is a sprocket wheel 38, which abuts the gland 33, said sprocket wheel 75 operating with the collar 37 in preventing longitudinal displacement of the member 35 during its rotation in the housing 30. A sprocket chain 39 is trained over the sprocket wheel 38 and it is through the medium of 80 this chain that the head 36 is whirled or revolved, either manually or from a suitable source of power in connection with the sprocket chain 39 or directly connected to the wheel 38 or a similar transmission 85 mounted upon the member 35.

The head 36 is hollow and radially disposed relative to the member 35. At the outer end of the head 36 are oppositely disposed elbow connections 40 and swiveled or 90 adjustably mounted relative to the connections 40 are elbow nozzles or ejector connections 41 having nozzles or ejectors 42. The nozzles or ejectors 42 are oscillatory relative to the connections 40 and one of said nozzles 95 or ejectors is curved, for a purpose that will hereinafter appear. The nozzles or ejectors are adapted to be oscillated in unison and move to and from each other to disseminate steam during the rotary movement 100 of the head 36.

To oscillate or adjust the nozzles or ejectors 42 during a rotation of the head 36, provision is made whereby the same can be accomplished at the outer end of the housing 105 30 when the ejectors or nozzles are projected into the opening or doorway 4. An operating rod 43 extends longitudinally of the tubular member 35 and the outer end of said rod is in screwthreaded engagement, as 110 at 44 with a head 45 closing the outer end of the housing 30. The outer end of the rod 43 has a conventional form of hand wheel or crank 46 whereby said rod can be adjusted longitudinally of the member 35, and the 115 inner end of the rod 43 protrudes from the head 36 and is reduced to form a stem 47. This stem is loosely held in engagement with an arm 48, carried by a cross head 49. The cross head 49 has the end thereof connected by pins or bolts 50 to links 51 and said links are connected to pins or studs 52 carried by the steam ejectors or nozzles 22.

The inward movement of the rod 43 is limited by the hand wheel 46 engaging a 125 cap 53 of a housing head 45 and with said rod in its innermost position, the connections between said rod and the ejectors or nozzles 42 is such that the nozzles are in parallelism, as illustrated in Fig. 1. An out- 130

ward movement of the rod 43 spreads the nozzles 42 and through the medium of the offset head 36 and the loose connection with the rod 47 the steam ejectors or nozzles can be adjusted to a desired inclination relative to the head 36 during a rotary movement of the member 35.

As shown in Fig. 1, the rotary injector head 36 is normally in proximity to the door 10 or shutter 10 and with the door or shutter open, the head 36 can be projected into the opening or doorway 4 whereby the steam ejectors or nozzles 42 can discharge steam throughout the chamber 1. To facilitate reciprocating the member 25, the outer end of the connection 26 is provided with a suitable handle 74 and to lock the member 25 in an adjusted position, a locking bar 55 is employed. This bar is fixed a boss 56 of 20 the connection 26 and extends through the boss 18 of the stuffing box 17. The locking bar 55 is in parallelism with the tube or pipe 24 and is provided with openings 57 to receive a pin 58. With the pin engaging 25 the boss 18 it is impossible for steam, under pressure in the casing 14 or the telescopic member 16 to displace the member 25 relative to the stuffing box 17. In lieu of the pin 28, the upper side of the locking bar 55 30 can be notched, as indicated at 59 in Fig. 4 and the boss 18 provided with a gravity dog or pawl 60 to engage in the notches of the locking bar. Such a lock will automatically secure the reciprocal steam injecting member 25 in a projected position and it is only necessary to elevate the dog or pawl 60 when it is desired to retract the blower.

In operation, it is only necessary to place the member 25 in a projected position, turn 40 on the steam or agent employed for removing soot and other foreign matter from the chamber 1 and the tubes or flues 2 thereof, revolve the member 35, and adjust the rod 43 in said member. By revolving the member 35 through the medium of the chain 39 and intermittently adjusting the rod 43 the ejectors or nozzles 42 are oscillated and throughout the operation of the blower the outlet ends of the ejectors or nozzles assume 45 the various positions shown in Fig. 11, consequently blasts or jets are produced within the chamber 1, as indicated by dotted lines in Fig. 5 of the drawings.

I attach considerable importance to the 55 fact that the steam ejectors or nozzles can be oscillated as the injector head is revolved, and it is by this action that steam is projected against the tubes or flues 2 to thoroughly remove soot and incrustations from 60 the same. By oscillating or adjusting the nozzles or ejectors, the striking area of the steam can be increased and decreased, and in using the term "striking area" I allude to that area of blasts or jets denoted by 65 dotted lines in Fig. 5, which includes such

space wherein steam is effective for removing soot and incrustations. I am aware of single nozzles that can be swung around in a chamber to discharge steam in various directions, but in the present instance there 70 are two co-operating nozzles that are moved in unison to increase and decrease the function of steam, without changing the pressure thereof, as a cleansing agent for tubes or flues. Undoubtedly the striking area of 75 steam could be increased and decreased by varying the pressure, but in contradistinction to a pressure variation, I have devised the co-operative nozzles, which when revolved, subject a large area to the action of 80 steam.

While in the drawings there are illustrated the preferred embodiments of my invention, it is to be understood that the structural elements are susceptible to such 85 changes, as in the size, shape and manner of assemblage, as fall within the scope of the appended claims.

What I claim is:—

1. In a blower, a reciprocal steam injecting member, a rotary injector head carried thereby, and oscillatory nozzles carried by said head and capable of being swung to and from each other.

2. In a blower, a reciprocal steam injecting member, a rotary injector head carried thereby, oscillatory nozzles carried by said head and capable of being swung to and from each other, and means for revolving said head.

3. In a blower, a reciprocal steam injecting member, a rotary injector head carried thereby, oscillatory nozzles carried by said head and capable of being swung to and from each other, and means for oscillating 105 said nozzles simultaneous with the rotary movement of said head.

4. In a blower, a rotary head, oscillatory nozzles carried thereby and capable of being swung to and from each other, and means 110 extending through said head adapted to oscillate said nozzles simultaneous with the rotary movement of said head.

5. A fuel economizing apparatus including an inclosed water circulating structure 115 located in the path of travel of products of combustion, a rotary head adapted to be projected into said structure, and oscillatory nozzles carried by said head and capable of being swung to and from each other and 120 adapted to be oscillated during a rotary movement of said head.

6. A fuel economizing apparatus including an inclosed water circulating structure located in the path of travel of products of 125 combustion, an injector head adapted to be projected into said structure, opposing nozzles carried thereby and adapted to receive steam through said head, and means for adjusting said nozzle from the exterior of said 130

- structure to increase and decrease the area of the steam jets from said nozzles.
7. A fuel economizing apparatus including an inclosed water circulating structure located in the path of travel of products of combustion, a reciprocal steam injecting member carried by said structure, a rotary injector head carried by said member and adapted to be projected into said structure, opposing oscillatory nozzles carried by said head, and means operable at said member for adjusting said nozzles to increase and decrease the area of the steam jets from said nozzles.
8. A fuel economizing apparatus including an inclosed water circulating structure located in the path of travel of products of combustion, a reciprocal steam injecting member supported by said structure, a rotary injector head carried by said member, and adapted to be projected into said structure by said member, means for locking said member in adjusted position, and opposing oscillatory nozzles carried by said head and capable of being swung to and from each other.
9. A fuel economizing apparatus including an inclosed water circulating structure located in the path of travel of products of combustion, a reciprocal steam injecting member supported by said structure, a rotary injector head carried by said member and adapted to be projected into said structure by said member, means for locking said member in adjusted position, opposing oscillatory nozzles carried by said head and capable of being swung to and from each other, and means for oscillating said nozzles simultaneous with the rotary movement of said head.
10. The combination with a boiler setting having a normally closed opening, of a reciprocal steam injecting member supported by said setting above the opening thereof, a rotary injector head carried by said member and adapted to be projected through the opening of said setting by said member, means for revolving said head, opposing nozzles carried by said head, and means adjustable at said member for moving said nozzles to and from each other relative to said head.
11. In a blower, the combination with a boiler setting having a normally closed opening, of a reciprocal steam injecting member supported by said boiler setting, means for locking said member in adjusted position, a rotary injector head supported by said member, means for revolving said head, opposing oscillatory nozzles carried by said head, and means for adjusting said nozzles to and from each other to increase and decrease the area of steam jets from said nozzles.
12. The combination with a boiler setting having an opening, of a casing at said boiler setting adapted to receive means, a reciprocal steam injecting member movable in and out of said casing, a rotary injector head supported by said member and adapted to be projected through the opening of said boiler setting, opposing nozzles carried by said head, and means for adjusting said nozzles to and from each other during the rotary movement of said head.
13. The combination with a boiler setting having a normally closed opening, of a casing at said boiler setting, a reciprocal steam injecting member movable into and out of said casing, a housing forming part of said member, a tubular member revolvably supported by said housing, a head carried by said member, opposing nozzles carried by said head, means extending longitudinally of said tubular member for adjusting said nozzles to and from each other relative to said head, and means on said tubular member to facilitate imparting a rotary movement thereto.
14. The combination with a boiler setting having a normally closed opening, of a housing movably supported adjacent said boiler setting, a tubular member revolvably mounted in said housing, an injector head carried by said member and adapted to be projected into the opening of said boiler setting by a movement of said housing, opposing nozzles carried by said head, and means extending longitudinally of said tubular member for adjusting said nozzles to and from each other during a rotary movement thereof.
15. A fuel economizing apparatus including an inclosed water circulating structure located in the path of travel of products of combustion, a steam injector head adapted to be projected into said structure, and opposing means distensible and retractile for increasing and decreasing the striking area of steam injected by said head.
16. A fuel economizing apparatus including an inclosed water circulating structure located in the path of travel of products of combustion, a rotary steam injector head adapted to be projected in said structure, and distensible and retractile opposing means adapted to be operated exteriorly of said structure for increasing and decreasing the striking area of steam injected by said head.
17. In a blower, a boiler setting, a rotary tubular member movable into and out of said boiler setting, an offset head carried thereby, opposing nozzles on said head, and means for adjusting said nozzles to increase and decrease the striking area of steam ejected thereby.
18. An injector for steam blowers comprising a revoluble head, and opposing oscillatory nozzles on said head and adapted

to be oscillated to and from each other in unison.

19. An injector for steam blowers comprising a revoluble head, oscillatory nozzles on said head, and means extending through said head for simultaneously adjusting said nozzles to and from each other to increase and decrease the striking area of steam ejected by said nozzles.
- 10 20. An injector for steam blowers comprising a rotary steam injecting head, and distensible and retractible opposing means on said head for increasing and decreasing the striking area of steam injected thereby.
- 15 21. The combination with a boiler setting, of a battery of blowers carried thereby, and each including a steam injecting head movable into and out of said boiler setting, and distensible and retractible opposing
- 20 means operatable interiorly of said boiler setting for increasing and decreasing the striking area of steam injected by said head.
22. The combination of a boiler setting of the vertical type, of a battery of blowers carried thereby and each including a steam injecting head movable into and out of said boiler setting, and opposing nozzles on said

head adapted to be oscillated after entering said setting.

23. The combination with a boiler setting 30 of the vertical type, of a battery of blowers carried thereby and each including opposing distensible and retractible nozzles, and means operatable exteriorly of said boiler setting for oscillating said nozzles after entering said setting to increase and decrease 35 the striking area of steam injected thereby.

24. The combination with a boiler setting of the vertical type, of a battery of blowers carried thereby each including a revoluble 40 steam injecting head movable into and out of said boiler setting, oscillatory opposing nozzles carried by each head, and means operatable exteriorly of said boiler setting for simultaneously revolving said head and 45 distending and retracting the nozzles carried thereby.

In testimony whereof I affix my signature in presence of two witnesses.

JAMES C. BENNETT.
